UNITED STATES PATENT OFFICE

EDWARD S. PETERSON, OF ELMWOOD PARK, AND LEONARD L. RUGGLES, OF WHEATON, ILLINOIS, ASSIGNEES TO RESERVE HOLDING COMPANY, OF KANSAS CITY, MISSOURI, A CORPORATION OF DELAWARE

TELEPHONE SYSTEM

Application filed August 6, 1928. Serial No. 297,631.

The present invention relates to telephone systems in general, but is concerned more particularly with semi-automatic magneto exchange (S. A. M. X.) telephone systems, although certain of its features are not confined specifically thereto.

The main object of the invention is the production of new and improved circuit arrangements for simplifying and reducing the amount of the equipment required in semi-automatic magneto telephone systems of the type exemplified by the disclosure of the co-pending Ruggles application, Serial No. 199,917, filed June 20, 1927, now Patent No. 1,752,543, and in his application Serial No. 237,140, filed December 2, 1927.

In each of the above disclosures, connections are set up between manual magneto lines by automatic switching apparatus responsive to control exercised over an operating trunk extending between the manual magneto exchange and a distant operating center.

One object of the invention is to avoid the use of a finder for connecting the operating trunk with a local connector on which a call is waiting and to use instead a connecting relay individual to each local connector to connect such connector to the operating trunk upon seizure.

A further object is to reduce the amount of equipment required by placing relay equipment within the equipment individual to the operating trunk, which supplements any connector to which the operating trunk is connected so that the equipment in the various individual connectors is reduced to a minimum. This relay equipment is referred to hereinafter as common sequence-control equipment.

A further object is the production of an arrangement for still further simplifying the connectors by omitting the code selecting devices individual to the respective connectors and by arranging a ringing relay controlled over the operating trunk to respond to control from the operating center which may be exercised by an operator's key or otherwise to signal the called subscriber.

It is a further object to arrange the common sequence-control equipment so that it

can be used interchangeably with different types of connectors so that the same operating trunk equipment may be used in any one of four types of exchanges as follows: (a) automatic-ringing, ring-off release, (b) automatic-ringing battery-holding, (c) key-ringing ring-off release, (d) key-ringing, battery-holding.

Another object is the arrangement whereby an alarm or other abnormal condition arising in semiautomatic magneto exchange (abbreviated S. A. M. X.) results in an alarm call being sent to the operating center over the operating trunk and in the alarm call being switched to a special operator's position in the operating center.

Other objects and features will become apparent upon a further perusal of the specification in connection with the accompanying drawings.

Referring now to the drawing comprising Figs. 1-14, they show by means of the usual circuit diagrams a sufficient amount of apparatus in a telephone system embodying the features of the invention to enable the invention to be understood. Figs. 1-10 are circuit diagrams, while Figs. 11-14 show the way in which Figs. 1-10 should be assembled in order to be understood best. Referring now to Figs. 1-10, Fig. 1 shows the operating-center equipment associated with the operating trunk.

Fig. 2 shows the emergency operating set and the alarm and signal relays in the S. A. M. X. associated with the operating trunk.

Fig. 3 shows the common sequence control equipment in which the operating trunks terminate in the S. A. M. X.

Fig. 4 shows a local connector, which is one of a plurality of connectors to which the apparatus of Figs. 2 and 3 is common. The local connector shown in this drawing has access to the line of substation A2 and to all the other lines terminating in the S. A. M. X. and is accessible to line switch LS of the substation A1 and also to the line switches in which the other lines terminate. It is assumed that the lines of substations A1 and A2 are party lines, for which reason the lines are indicated as common to several sub-

stations by the conventional common connection symbols associated therewith. Fig. 4 shows also the master switch common to the line switch LS and other line switches. It has been assumed that there are more than ten connectors in the S. A. M. X., in which case one line switch group, being limited to ten trunks, cannot reach all the connectors with the result that two line switch groups, each having its own master switch, have been provided. About half the line switches belong to one group and remaining ones to the other group. The line switch LS is assumed to be a line switch of group #1, and the master switch shown is the master switch of group 1. No line switch of group #2 nor the master switch of group #2 is shown, but the connections of group #2 will become apparent as the description progresses.

It will be noted that, in Figs. 2, 3, and 4, there are numerous conductors brought out to numbered terminals. These terminals indicate to where the conductor extends, and all terminals bearing the same reference number are assumed to be connected together.

The connector of Fig. 4 is arranged for key-ringing and battery-holding, that is, the ringing current is relayed in response to impulses received over the operating trunk from the operating center and when a connector is once seized it is held in a seized condition as long as current is flowing over the calling line.

Fig. 5 shows a connector similar to the connector of Fig. 4 except that it is arranged for ring-off release, that is, the connection is not maintained by the flow of current over a calling line, but is maintained until the calling subscriber replaces his receiver and rings off (makes a momentary application of ringing current by turning his crank in the usual manner).

The connector of Fig. 6 is a battery holding connector as is the connector of Fig. 4, but is arranged for automatic ringing instead of for key-ringing, that is, a party selecting digit is received over the operating trunk to set a code selector individual to the connector after the connector is set and the ringing is accomplished locally in accordance with the position of the code selector.

The connector of Fig. 7 is similar to the connector of Fig. 5 except that it is provided with automatic ringing as mentioned above in connection with Fig. 6 instead of with key-ringing as mentioned in connection with Fig. 5.

Fig. 8 shows a toll connector arranged to be operated over a toll trunk from the operating center to set up connections to and from S. A. M. X. lines.

This toll connector is arranged for key ringing so that it may be used in connection with either Fig. 4 or Fig. 5.

Fig. 9 is a similar toll connector, except

that it is arranged for automatic ringing so that it may be used in connection with Fig. 6 or Fig. 7.

Fig. 10 shows the operating-center end of the toll line and may be used in connection with Fig. 8 or Fig. 9.

Referring now to Figs. 11-14, Fig. 11 shows how Figs. 1-4 and Figs. 8-10 assemble together for use in a key-ringing-battery-holding S. A. M. X.; Fig. 12 shows how Figs. 1-3, 5, 8, and 10 assemble together for use in a key-ringing-ring-off release S. A. M. X.; Fig. 13 shows how Figs. 1-3, 6, 9, and 10 assemble together in an automatic-ringing battery-holding S. A. M. X.; while Fig. 14 shows how Figs. 1-3, 7, 9, and 10 assemble together for use in an automatic-ringing ring-off release S. A. M. X.

Detailed description

The invention having been described generally, a detailed description of the operation of the apparatus shown will now be given. For this purpose it will be assumed that Figs. 1-4, 8, and 10 are assembled as shown in Fig. 11.

Handling a local connection

It will now be assumed that the subscriber at substation A1 desires to converse with the subscriber at substation A2. The subscriber at substation A1 operates the hand generator at his telephone in the usual manner, projecting ringing current over his line to the line switch LS in the exchange. This ringing current passes through the lower winding of line relay 404 of the line switch LS. Upon operating, line relay 404 locks itself at its inner upper contact to ground by way of the line switch alarm conductor leading to terminal 206. Terminal 206 is grounded in Fig. 2 by way of the line switch alarm relay 236, which relay is provided for a purpose to be explained hereinafter. At its upper armature, relay 404 places ground on private normal conductor 402 so as to guard the line against intrusion. At its middle armature, relay 404 closes a circuit for the pull-down winding of magnet 405 by way of the open-chain conductor extending from the master switch through contacts of all the line switches in series, at the same time disconnecting the open-chain conductor from all the succeeding line switches in the chain.

If the chain is clear, as shown, the closing of the circuit through relay 405 results in an operation of the delay relay in the master switch, the current for this purpose flowing through the high resistance winding of the delay relay. Magnet 405 cannot energize until the delay relay operates and shunts its low resistance winding around its high resistance winding. This operation is delayed slightly by the short circuited upper winding of the relay so as to give time for a complete resto-

ration and realignment of the plunger of any line switch that may happen to be restoring and realigning at this time before any line switch is permitted to operate. As soon as 5 the delay relay operates, it closes a circuit through its upper winding in parallel with its lower winding, whereupon magnet 405 of the line switch operates and forces the springs 408-411 into engagement with their 10 respective associated contacts of the trunk line extended to the local connector shown in the drawings. This is accomplished by arm 406, which arm also disconnects the locking winding of line relay 404 from the alarm 15 conductor 206 and connects it to the common locking conductor 208, which locking conductor is grounded through relay 332 Fig. 3 as will be pointed out subsequently. The cut-off arm 407 is operated to disconnect the lower 20 winding of relay 404 from in bridge of the calling line. As the result of the operation of springs 408 and 411, the talking conductors of the calling line are connected to the corresponding conductors of the connector. At 25 contact spring 409, conductor 402 is extended to the normally-grounded release-trunk conductor 413 of the connector, which conductor at this time is grounded at the contacts of relays 435 and 436. At contact spring 416, 30 a ground potential is extended to "hold" conductor 414, which is a test conductor of the master switch, causing the usual advance of the master switch responsive to the operation of the test relay which advances the master 35 switch by connecting the grounded "chain-in" conductor 204 to the winding of the locking relay. The test relay also disconnects ground from the lower terminal of the delay relay so as to prevent any further line switch operation 40 at this time. The open-chain relay is operated from contacts of the locking relay and opens a further point in the chain circuit extending to the line switches, at the same time placing a shunt around its normally- 45 open upper winding so as to make the relay slow acting in order to keep the chain open for a slight interval after the master switch has finished its operation. The actual movement of the master switch segment takes 50 place at this time in a counter-clockwise direction under the control of the usual U spring (not shown).

When the master switch advances to a new position, the test relay falls back provided 55 the trunk #2 is idle permitting the locking relay to fall back and catch and hold the master switch in this position. The open-chain relay falls back a moment later, placing the master switch in normal condition, the delay 60 relay having fallen back responsive to the opening of the chain occurring upon the operation of the test relay.

In the connector, the connecting relay 437 operates over hold conductor 416 from the 65 ground potential supplied thereto through

contact spring 410 and through contacts of relay 436. Upon operating, relay 437 operatively associates the associated connector with the common sequence control equipment of Fig. 3.

When the locking circuit of line relay 404 is transferred from the alarm conductor 206 to the common locking conductor 208, as above pointed out, the lower winding of relay 332 is operated over the common locking conductor (see terminal 208 Fig. 2) through contacts of relay 335. Relay 332 at its inner armature disconnects the inner terminals of the associated left-hand repeated coil windings from ground and connects them to battery through the differential relay 333 and the upper winding of impulse relay 334. This operation places battery through relays 333 and 334 on both conductors of the operating trunks with a result to be pointed out subsequently. As a further result of the operation of relay 332, the two chain control relays of the master switches of the two groups are energized at the two lower armatures by ground potential applied to terminals 205 and 214. Terminal 205 is connected to the open-chain relay of the master switch shown in Fig. 4, while terminal 214 is connected to the corresponding relay in the second group. This operates the both open-chain relay so as to prevent further line switch operation until the call being handled has taken its regular course.

At armatures 349 and 350, relay 332 removes ground from the alarm-ground conductor and from the ground-control conductor for a purpose to be hereinafter explained, while at its upper contacts relay 332 connects up the condenser between the inner terminals of the right hand repeating coil windings, thereby preparing a talking circuit.

As a result of the connecting of the battery potential through relays 333 and 334 to the minus and plus trunk conductors of the operating trunk, a current flows over the two conductors of the operating trunk in parallel to ground over a circuit path to be traced subsequently, bringing about an energization of line relay 334. Differential ringing control relay 332, however, does not operate owing to the fact that the current flow in one winding counterbalances the flow in the other winding. Upon operating, relay 334 closes a circuit for release relay 335 in series with the series relay 336.

Relay 335 operates and at its inner lower armature closes a locking circuit for itself through the inner lower contacts of relay 340, thereby preparing an operating circuit for series relay 336 and an impulsing circuit through the lower armature, normal, of relay 342 for the vertical magnet of the local connector #1 which is now connected to conductor 303 through contacts of connecting relay 437. Due to the fact that the vertical magnet

is now shunted around the series relay 336, this relay does not operate in series with the relatively high resistance release relay 335. At its inner upper armature, relay 335 prepares locking circuits for relays 341 and 342, while at its upper armature it closes a circuit for the slow acting clear-out control relay 334, which relay operates and prepares a circuit for clear-out relay 345. At its lower armature relay 335 closes a local circuit for relay 332 through resistance 352, opening the initial circuit, whereupon the line relay 404, Fig. 4, falls back. The circuits in the S. A. M. X. are now prepared for operating local connector in accordance with the desired number.

In the operating center, line relay 111 is normally connected between ground and the lower conductor of the operating trunk by way of contacts of relays 101, 104, 105, and 113, and is connected with the upper conductor of the operating trunk through contacts of relays 102 and 103 in parallel, the upper winding of differential relay 115 being in series with the upper operating trunk conductor and the lower winding being in series with the lower operating trunk conductor. Relay 111 energizes when the battery potential is applied to the operating trunk in the S. A. M. X. as above pointed out, but the differential relay 115 does not operate at this time. Upon operating, relay 111 grounds the locking conductor 131 at its upper armature; closes at its lower armature a circuit for relay 112 from ground through armature 119 of relay 102, and contacts of relays 115 and 114. This circuit is completed to battery through the inner upper contacts of relay 114 and the operating magnet of the sender selector. At its inner upper contacts, relay 111 connects the test wiper of the sender selector to the junction of the winding of the operating magnet and winding of relay 112, with the result that the operating magnet is operated directly from the test wiper in case the sender on which the sender selector is standing is busy, the switching relay 112 being short circuited in this event. The self-interrupting operating magnet operates in a buzzer-like manner and advances the wipers of the sender selector until an idle sender is reached. Assuming that the sender shown in the drawings is the first idle one reached, the wipers of the sender selector stop thereon owing to the absence of ground potential on the test contact thereof, whereupon relay 112 operates in series with the operating magnet, but the operating magnet does not operate at this time owing to the relatively high resistance of relay 112. Upon operating, relay 112 disconnects the test wiper from the junction of its own winding and that of the operating magnet connects it to ground instead, thereby grounding the test wiper of the sender selector so as to make the

seized sender busy to the other sender selectors. At its remaining armatures, relay 112 connects up the corresponding wipers of the sender selector.

The impulsing wiper is now grounded at the impulse contacts of the sender, with the result that a circuit is now closed from the grounded impulse contacts through the impulse wiper of the sender selector, armature 120, relay 110, contacts of relays 109 and 108, and contacts of relay 105 to battery through winding of relay 105. Relays 105 and 111 operate in this circuit and relay 105 closes a locking circuit for itself at its inner upper armature to the locking conductor 131 through contacts of relay 104. At its lower armature, relay 105 opens a point in the circuit of the release magnet of the code switch, at the same time preparing a circuit for relay 106. At two upper armatures, relay 105 disconnects the simplex leg of the operating trunk from relay 111 and connects it instead to ground by way of repeating relay 110, closing a local holding circuit for relay 111 through resistance 116. Relay 110 now remains energized over the operating trunk.

As a result of the grounding of the test conductor of the sender through the test wiper of the sender selector, circuit arrangements with which this invention is not concerned are brought into play to cause the operator to be signalled and to cause the contacts in the sender to close the connection through to the operator's headset.

The operator now converses with the calling subscriber in the usual manner and ascertains the desired number. Under the assumption that the subscriber desired is the subscriber at substation A2 Fig. 4, the operator receives the number of this subscriber, which number may be, for example, 115, the final digit indicating the particular party on the line. The operator is provided with a key set (not shown) for controlling the sender. Upon learning the number the operator manipulates her key-set in accordance therewith and pushes the start key thereof, whereupon her headset and key-set are automatically disconnected from the sender and the transmission of impulses begins.

When the first digit 1 is retransmitted by the sender at the impulse-sending contacts thereof, relays 110 and 334 respond, and relay 110 closes a circuit for series relay 106 through the lower armature of relay 105. Relay 106 operates and closes a circuit for the upper winding of the two-step relay 107, whereupon relay 107 operates its first step locking contacts to lock itself to a branch of the grounded locking conductor 131 through the lower contacts of stop relay 104. No current flows in this locking circuit as long as the initial circuit remains closed at the contacts of relay 106. However, when relay 106 falls back at the end of the first digit

and opens the initial circuit of relay 107 both windings energize in series, operating the relay through its second step to transfer the operating circuit, at the upper contacts of 5 the relay, to relay 108.

As a result, relay 108 operates through its first step at the beginning of the second digit 1 and when relay 106 again falls back at the end of the second digit 1, relay 108 operates 10 through its second step. At its lower contacts, relay 108 connects the rotary magnet of the code switch in parallel with series relay 106 so as to enable the code switch to respond to the stations-selecting digits. At its inner 15 upper armature, relay 108 transfers the relay operating circuit to relay 109, while at its two upper armatures it shifts the upper terminal of relay 110 to battery through the resistance 117 and applies a holding ground 20 to the operating trunk conductor so as to maintain the established circuit conditions in the S. A. M. X.

When the station digit 5 is retransmitted, it is repeated by relay 110 to the rotary magnet 25 of the code switch in parallel with relay 106, with the result that the code switch is advanced five steps and its wiper comes to rest on the fifth code conductor. Relay 106 responds to the first of the series of impulses 30 and, being slow acting, remains operated throughout the digit. When relay 106 operates it closes an operating circuit for the upper winding of the two-step relay 109 which operates through its first step, and, 35 when relay 106 falls back, it operates through its second step. At its lower contacts, relay 109 connects the pick-up conductor of the code machine to pick-up relay 102; at its middle lower armature it disconnects the 40 rotary magnet of the code switch from in multiple with the series relay 106; and at its upper armature it opens the circuit of relay 110 which falls back and again operates through relay 106 but without any particular 45 result at this time.

Before proceeding further with the description of the operation in the operating center, it will be well to take up the operation in the S. A. M. X.

50 When the first digit 1 is transmitted by the sender, line relay 334 of the common sequence-control equipment, Fig. 3, falls back and delivers an impulse to the vertical magnet of local connector #1, Fig. 4, over a circuit path which starts from ground through the inner lower contacts of relay 340 and includes the inner lower armature of release relay 335, normally closed contacts controlled by the armature of line relay 354, lower 55 armature, normal, of relay 342, vertical operating conductor 303, and contacts of connecting relay 437 to the vertical magnet. The 60 vertical magnet responds by raising the associated wipers opposite the first level of bank 65 contacts. When this occurs, the off-normal

contacts associated with the release magnet of the connector operate to prepare a circuit for the release magnet, which circuit is now open owing to the fact that relay 434 is energized from the contacts of line relay 432 70 which is energized over the calling line in series with battery feed impedance 431. At the off-normal contacts associated with conductor 415, an additional guarding potential is placed on the trunk line as regards to the master switch, by way of the lower test bank 75 of the master switch.

In the common sequence-control equipment, the series relay 336 is operated in parallel with the vertical magnet of the connector, being so designed with respect to the vertical magnet and release relay 335 that it will operate and remain operated throughout a series of impulses. Upon operating, series relay 336 closes a circuit for the auxiliary 80 relay 337 at its upper armature, whereupon relay 337 operates and closes at its upper armature a circuit for relay 342 which operates and locks itself to the call-lamp conductor at its upper armature, preparing a circuit for 85 relay 342 at its lower armature.

It will be noted that the release relay 335 is short circuited each time an impulse is delivered to the magnet operating circuit and to series relay 336. This does not result in 90 a deenergization of the release relay during a series of impulses because a short circuited relay is slow to fall back as is well known.

When the first digit is terminated, relay 336 falls back, followed by the deenergization of relay 337. At its upper armature, relay 337 completes the circuit of relay 342 through the lower contacts of relay 343. Relay 342 operates and locks itself to ground 100 through the inner upper armature of release relay 335, opening its initial circuit. At its upper armature, relay 342 opens the locking circuit of relay 343, which relay falls back. At its lower armature, relay 342 shifts the 105 impulse conductor from the vertical magnet to the rotary magnet.

When the second digit 1 is received over the operating trunk from the sender in the operating center, line relay 334 again falls back momentarily, delivering another impulse to series relay 336 and over the operating conductor to the connector. Since relay 342 is operated at this time, the impulse is delivered through the lower armature, operated of relay 342, armature 355, normal, lower armature of relay 388 rotary operating conductor 304, and contacts of connecting relay 437 to the rotary magnet. The rotary magnet responds and rotates the wipers of the connector into engagement with the contacts in which the line of substation A terminates.

It will be noted that the test wiper of the connector is now connected through contacts of relay 437 and by way of test conductor 311 130

to the lower armature of series relay 336. With series relay 336 operated during the rotary movement of the connector, the test conductor is extended to the winding of the busy test relay 340. In case the line is busy, relay 340 is energized from ground on the busy test contact when the wipers come to rest upon the bank contacts of the called line, with the result that when series relay 336 falls back it closes a locking circuit for the busy relay from the grounded call-lamp conductor through the inner upper armature, normal, of relay 338, inner upper armature, operated, of busy relay 340 normally closed contacts controlled by the lower armature of relay 336, and the middle lower armature of relay 338.

When the auxiliary relay 337 falls back, responsive to the energization of series relay 336, with busy relay 340 operated, the busy-tone source is connected through contacts of relays 341, 340 and 337 to the lower talking conductor, the upper talking conductor being grounded at this time by contacts of relay 340, giving a busy tone to the calling subscriber to inform him that the called line is busy. Upon hearing the busy tone, the calling subscriber is expected to replace his receiver and allow the equipment to clear out. Assuming now that the desired line is idle when called, there is no ground potential encountered upon the test contact of the line by the test wiper of the connector when it lands thereon, and busy relay 340 does not operate. In this case, when series relay 336 falls back it connects the test conductor of the connector at its lower armature to ground by way of the upper winding of test relay 341, this upper winding being grounded at this time by way of contacts of relays 340 and 338 to the call-lamp conductor.

As a result, relay 341 energizes over the test conductor of the connector and through the private normal conductor of the called line in series with the bridge-cut-off winding of the called line switch corresponding to the bridge-cut-off winding, the lower winding, of the line switch LS. The bridge-cut-off winding energizes and clears the called line. Relay 341, upon operating, closes a locking circuit for itself at its inner lower armature through the inner upper armature of release relay 335; extends the ground potential on the called lamp conductor through contacts of relay 338 to the test wiper at its armature 353 so as to place a more direct ground potential on the test conductor of the called line; disconnects the operating conductor from the rotary magnet at armature 355 and connects it to the code-selector operating conductor 312; and prepares the ringing circuit at armature 356.

From the foregoing it will be seen that the connector has now been positioned on the contacts of the desired line, that the line has

been seized, and that the ringing circuit has been prepared and is now under the control of the differential relay 332.

Returning now to the circuits in the operating center, the operation therein has been described to the point where the pick-up conductor from the common code machine has been connected through contacts of relay 109 to pick-up relay 102. The code machine is shown only diagrammatically, but it will be understood that the contact springs shown are operated in the proper sequence so that the pick-up conductor is grounded first, following which the various other contacts are operated in accordance with codes assigned to the positions of the code switch, after which the stop conductor is grounded.

Now, when the pick-up conductor is grounded after relay 109 has operated, a circuit is closed for pick-up relay 102, which thereupon operates and locks itself through the lower armature of stop relay 104 to the grounded locking conductor 131. As a further result of its operation, relay 102 prepares a circuit for stop relay 104 at its lower armature; removes a shunt from the upper contacts of ringing relay 103 at its upper armature; closes a circuit for relay 101 at its inner upper armature; and at armature 119 opens the circuit of switching relay 112 associated with the sender selector, whereupon relay 112 falls back and frees the sender selector. As the result of the closure of the circuit for relay 101, this relay operates and opens the circuit of relay 111 at its upper contacts. Relay 111 falls back after a short interval and removes ground at its upper armature locking conductor 131, but this conductor is now maintained grounded through contacts of the relays 102 and 101. The lower winding of ringing relay 103 is now connected through the inner lower contacts of relay 102 to the wiper of the code switch which is standing on the #5 code conductor and therefore receives the impulses corresponding to the #5 code. Each time one of these impulses is delivered, relay 103 operates and opens the circuit through the upper winding of the differential relay 115 and over the upper conductor of the operating trunk, permitting the differential relay 115 to operate, but without any particular result at this time since its armature is ungrounded at armature 119 of relay 102.

In the S. A. M. X., differential relay 333 operates each time the line is unbalanced as above pointed out. Each time it does so, it applies ringing current at its lower armature and through armature 356 to the minus ringing conductor which is now connected through contacts of connecting relay 357 to the minus wiper of the connector, and at its inner armature it applies ground to plus ringing conductor 308 which is now connected through contacts of connecting relay 437 to

the plus wiper of the connector. The differential relay restores each time a ringing impulse is ended. As the result, ringing current is placed on the called line by the differential ringing relay 333 in accordance with the code placed on the #5 code conductor by the code machine shown in Fig. 1.

When the stop conductor of the code machine is grounded at the end of the code period, stop relay 304 is energized over the stop conductor through contacts of pick-up relay 102. Upon operating, relay 104 locks itself energized through contacts of ringing relay 103 at its inner lower armature; unlocks pick-up relay 102 and counting relays 107-109 at its lower armature; unlocks relay 105 at its inner upper armature; and at its upper armature it extends a connection from the upper winding of relay 103 through the normally closed contacts controlled by the middle upper armature of relay 105 and through normally closed contacts controlled by the upper armature relay 113 to the lower operating-trunk conductor, a parallel connection being extended to the upper operating-trunk conductor through contacts of relays 102 and 103.

As a result of this application of battery potential to the operating trunk, instead of the ground potential previously applied thereto, through the middle upper armature of relay 108 and the middle upper armature of relay 105, line relay 334 in the S. A. M. X.

Fig. 3 falls back and relay 103 in the operating center does not operate at this time. Upon falling back, line relay 334 places a shunt around release relay 335, incidentally operating series relay 336. Release relay 335 falls back after a slight interval and unlocks relays 341 and 342 at its inner upper armature; removes ground at its upper armature from the call lamp conductor opening the circuit of the clear-out control relay 344, but this relay, being slow-acting, does not fall back immediately. As a result, the upper armature of relay 335 closes a circuit through the inner upper armature of relay 344 for clear-out relay 345. Since switching relay 341 has been energized, relay 346 has been energized by the upper armature of the switching relay through the inner armature of relay 347, and, being slow-acting, is still operated at this time. That being the case, when relay 345 operates through contacts of relay 344 it extends a momentary impulse to the switch-through conductor 307, operating the switch-through relay 436 through contacts of the connecting relay 437. Relay 436 locks itself to the grounded conductor 414, at the same time opening the circuit of connecting relay 437. Connecting relay 437 thereupon falls back and disassociates the local connector #1 from the common sequence-control equipment. At its inner upper armature, relay 436

opens the normal ground connection to conductor 413, but this ground connection has been replaced previously by a connection through the upper armature of the operated relay 434. At another of its upper armatures, relay 436 opens a point in the circuit of the release magnet; at another upper armature it removes ground at one point from the all-trunks-busy conductor, and applies ground directly to the test wiper of the connector to replace the ground potential removed therefrom upon the deenergization of relay 437; and at its upper and lower armatures it connects the incoming minus and plus conductors 412 and 416 to the corresponding wipers of the connector, thereby completing the talking connection between the calling line and the called line.

In the common sequence control equipment in Fig. 3, relays 344 and 346 fall back after an interval but produce no further result. As a further result of the deenergization of the release relay 335 of the common sequence control equipment, the locking circuit of relay 332 through resistance 352 is opened, whereupon relay 332 falls back and replaces ground on both conductors of the operating trunk, at the same time removing ground from both chain control conductors at its lower armatures so as to permit the open chain relay of each of the two master switches to fall back and allow calls to be made.

It may be pointed out that in case the clear-out condition is performed following a busy condition of the called line or in case of a false call, the switching relay 341 is not operated, in which case relay 346 is not operated through the upper armature of relay 341, and the clear-out impulse is passed to the release conductor 306 instead of to the switch-through conductor. In this case, the release impulse comes in and locks up the connecting relay 437 by means of its left hand winding, at the same time closing a circuit for the slow-acting release relay 435. Relay 435 in this case removes ground from conductor 413 and brings about the release of line switch and connector in a manner to be pointed out hereinafter. When the release pulse ends, the circuit of relay 435 is opened and relay 437 falls back to disconnect the connector from the common equipment.

In the operating center, relay 103, Fig. 1 now energizes over the operating trunk because ground potential is now applied to both operating trunk conductors and it removes ground potential from the locking circuit of stop relay 104, permitting the stop relay to fall back and restore the simplex leg of the operating trunk to its normal path to ground by way of line relay 111 in readiness for the next call over the operating trunk.

When the conversation is completed, the

calling subscriber replaces his receiver, whereupon current flow over conductors 401 and 403 and through impedance 431 and relay 432 ceases, permitting relay 432 to fall back and open the circuit of relay 434. Relay 434 falls back after a short interval and removes ground potential from conductor 413, relay 436 being operated at this time. When the ground potential is removed from conductor 413, magnet 405 of the line switch is deenergized and the line switch restores to normal. When the contact spring 410 breaks engagement with the associated contact, it removes ground from the hold conductor 414, opening the circuit of cut-through relay 436 of the connector, which relay thereupon restores and completes the release magnet circuit through contacts of relay 434 and the off-normal contacts associated with the release magnet. The release magnet now energizes from the battery potential supplied thereto over the release signal conductor 201 through the release relay 231, Fig. 2. When the normal position of the switch is reached the release magnet circuit is opened and the release magnet deenergizes. The operation of the release signal relay 231, Fig. 2, will be explained hereinafter.

30 *Handling an outgoing toll call*

It will now be assumed that the subscriber at substation A desires to set up a connection to a line outside of the S. A. M. X., which connections are handled by the toll operator. 35 In order to do this, the subscriber removes his receiver and causes his line switch LS to operate and seize a connector in the hereinbefore described manner, the local connector #1, Fig. 4, for example, whereupon the local connector is associated with the common sequence control equipment by the operation of relay 437 as hereinbefore described and the operating trunk is placed in calling condition as before. 40 When the operator is signalled by the operation of the sender selector of Fig. 1 seizing a sender, she converses with the calling subscriber and learns the destination of the call. The call subscribers are usually instructed to ask for "long distance". The operator now sets up the digit 0 on her key-set whereupon the sender retransmits the digit and switches through by means of its switch-through contacts. When the switch-through operation is performed under this condition, counting relay 109 has not been operated and a circuit is closed immediately through contacts of the operated relay 112 and the non-operated relay 109 for the stop relay 104. 55 Relay 104 operates to clear-out the equipment in the manner described hereinbefore.

In the S. A. M. X., the single digit 0 is transmitted from the common sequence control equipment over the vertical operating conductor 303 as described hereinbefore.

This operates the local connection #1 of Fig. 4 until its wipers stand opposite the tenth level of bank contacts. When the tenth level is reached, the "0"-level springs of the connector close and extend ground through contacts of connecting relay 437 to the "0"-level conductor 310, operating the "0"-level relay 338 so as to alter the circuits of the common sequence control equipment to permit a hunting action on the tenth level. This operation of relay 338 occurs upon the receipt of the tenth impulse by the connector and while series relay 336 and the series auxiliary relay 337 are still operated. With relays 337 and 338, operated, a circuit is closed from the call lamp conductor, which is grounded at the upper contacts of relay 335, through the inner upper armature operated of relay 338, inner upper armature of relay 337, and the inner lower armature of relay 338 for stepping relay 339. Upon operating, relay 339 prepares a circuit for the rotary magnet of the connector over the rotary conductor 304 at its lower armature, and at its inner lower armature it locks itself energized by grounding the test wiper of the connector by way of the test conductor 311. This locking circuit includes the interrupter contacts of the rotary magnet of the connector, contacts of relay 437, interrupter conductor 305, and the inner lower armature of "0"-level relay 338.

"0"-level relay 338 closes at its upper contacts a holding circuit for line relay 334 through contact of relay 341 so as to hold up the clear-out operation until an idle trunk is selected.

When series relay 336 falls back at the end of the digit, it opens the circuit of relay 337, whereupon relay 337 falls back and starts the rotary movement by closing at the normally closed contacts controlled by its inner upper armature a circuit from the grounded call-lamp conductor through the inner upper armature, operated, of relay 338 for the rotary magnet through the lower contacts of stepping relay 339 and over conductor 304. The rotary magnet of the connector shown in Fig. 4 operates and advances the wipers into engagement with the first set of bank contacts in the tenth level and, near the end of its stroke, opens its interrupter contacts, deenergizing stepping relay 339. Relay 339, on falling back, opens the circuit of the rotary magnet, whereupon the rotary magnet falls back again and closes its interrupter contacts.

The further operation depends upon whether the trunk line terminating in the first set of bank contacts is busy or idle. If the trunk line extending from this set of bank contacts is busy, a ground potential is encountered on test contact thereof by the test wiper of the connector, furnishing a reoperating circuit for the stepping relay 338 through the interrupter contacts and the in-

ner lower contacts of relay 338. When stepping relay 339 reoperates it again completes the rotary magnet circuit at its lower armature.

This alternate operation of stepping relay 339 and the rotary magnet of the connector continues until an idle trunk line is reached, which trunk line may be assumed is the one comprising conductors 804—807 and extending the toll connector shown in Fig. 9. When this trunk line is reached, no ground potential is encountered by the test wiper of the connector and the stepping relay 339 does not again operate. As the result, switching relay 341, whose upper winding has been short circuited by the ground potential encountered on busy test contacts, now operates in series with stepping relay 339 over the interrupter and test conductors in series and through the interrupter contacts of the relay magnet. Upon operating, relay 341 causes the switch-through operation before described and opens at its upper armature the holding circuit of line relay 334, permitting the equipment to clear-out as before.

Responsive to the seizure of the trunk line comprising conductors 804—807, ringing relay 821, Fig. 8, responds to the ground potential extended thereto over conductor 805 through the test wiper of the connector shown in Fig. 4 and through contacts of relay 828 and 824 and applies ringing current to the toll trunk. Relay 821 also closes a circuit for the vibrating-type relay 823 which operates and vibrates its contacts for awhile after which the contacts come firmly into engagement allowing the slow-to-operate relay 824 to pull-up and shift the energizing ground potential from relay 821 and lock relay 824 energized. Relays 821 and 823 now fall back and the application of ringing current is ended.

In Fig. 10, the ring-up relay 1003, which is shunted around the condenser associated with the left-hand repeating coil winding and connected in series with another condenser of similar capacity, responds to the ringing current and locks itself mechanically subject to the operation of cut-off relay 1002, by the standard interlocking arrangement used in connection with ring-up and cut-off relays. Upon operating, relay 1003 closes a circuit for the busy lamp at the toll board and the busy lamp at the special position and also closes a circuit for the call-lamp at the toll board.

Upon perceiving the lighted condition of the call-lamp, the toll operator inserts the plug of an idle cord circuit into the jack J2, whereupon the marginal sleeve relay 1001 operates over the sleeve of the plug and jack, and the cut-off relay 1002 is operated from the upper jack contacts to extinguish the call lamp and close an alternate circuit for the busy lamp to replace the circuit opened when

relay 1003 falls back responsive to being unlocked mechanically by relay 1002. The cord circuit used by the toll operator is such that no difference of potential is now brought about across the talking conductors so that relay 1005 does not operate at this time.

Incidentally, relay 1002 at its inner lower armature connects the left hand repeating coil inner terminals directly together and at its lower armature grounds the tied-together inner terminals of the repeating coil, operating line relay 827 of the connector of Fig. 8 over the two conductors of toll trunk in parallel, and through the two windings of the differential relay 826. Release 827 is operated by line relay 826, and at its upper armature applies ground to release trunk conductor 805 so as to maintain this toll trunk guarded as long as the operator has her plug in the jack at the toll board. Incidentally, relay 824 falls back at this time.

The toll operator now converses with the calling subscriber and completes the toll connection immediately in case it is to a near-by line. In case the call is to a line that cannot be reached immediately, the toll operator request the calling subscriber to replace his receiver and he is recalled when the connection is ready to the distant line and the recall is handled in the same manner as an incoming toll call, which will be described in detail hereinafter.

When the calling subscriber at substation A1 replaces his receiver, the local connector of Fig. 4 releases in the manner hereinbefore pointed out.

When the operator at the toll board shown in Fig. 10 removes her plug from the jack J2, the relays associated with the jack fall back and the simplex circuit over the toll line is opened, permitting line relay 826 and release relay 827 of the toll connector to fall back and remove the guarding potential from conductor 805. There is an incidental operation of the vertical and release magnets of the toll connector at this time as may be observed from an inspection.

Handling an incoming toll call

It will now be assumed that the operator at the toll board shown in Fig. 10 receives a call intended for the line of substation A2, Fig. 4. In order to complete this call to the line of substation A2, the operator inserts the calling plug of a cord into the jack J2, assuming that the toll trunk shown is idle as indicated by the unlighted condition of the associated busy lamp, whereupon relays 1001 and 1002 operate through the sleeve of the plug and jack and through the upper contacts of the jack, respectively. Relay 1002 lights the busy lamp as before and closes the simplex circuit by shunting the condenser associated to the right-hand repeating coil windings at its inner lower armature and by

grounding the tied-together inner terminals of the left hand repeated coil windings at its lower armature through contacts of relay 1004.

5 When this occurs line relay 826, and release relay 827, Fig. 8, operate as previously described, preparing the toll connector for operation.

When the operator turns her calling device (not shown) off-normal, which calling device is associated with her cord circuit, the marginal sleeve relay 1001 is caused to fall back by a reduction in the current-flow therethrough, whereupon it closes a circuit 10 through contacts of the operated relay 1002 for the dial-off-normal relay 1004. At its upper armature, relay 1004 connects the simplex leg of the toll trunk to the tip of the jack J2 and at its lower armature it connects the ring of the jack J2 to ground 15 through contacts of relay 1002, at the same time disconnecting the simplex leg of the toll trunk from ground at this point so, that the ground connection is maintained through 20 the tip and ring contacts of the jack J2 in series with the calling device now connected across the tip and ring conductors of the cord circuit. As the dial rotates back to normal, it interrupts the simplex leg of the toll trunk, producing a series 25 of interruptions in the circuit of line relay 826, Fig. 8, in accordance with the first digit in the number of the line of substation A2. Each time the circuit is opened, relay 826 30 falls back and closes a circuit for the vertical magnet, the circuit at the time of its first closure including the lower armature, operated, of relay 827 the normally closed associated off-normal contacts, and series relay 828. The slow acting series relay 828 operates 35 when the first impulse is delivered and remains operated throughout the entire series. Relay 828 serves to maintain its own circuit and that of the vertical magnet intact after the off-normal contacts have shifted 40 as they do upon the first vertical step.

At the end of the digit, relay 828 falls back and transfers the operating circuit from the vertical magnet to the rotary magnet.

50 The marginal relay 1001 Fig. 10 falls back and restores the circuits to their previous condition at the end of the digit, but is reoperated again when the calling device is turned off-normal for the second digit.

55 When the second digit is received in the connector in the form of a second plurality of deenergizations of line relay 826, the impulses delivered by relay 826 pass through the lower armature, operated, of relay 827, 60 the normally-open associated off-normal contacts, the armature normal, relay 828, and contacts of relays 829 and 831 to the rotary magnet. The rotary magnet responds to the series of impulses by rotating the wipers of 65 the connector into engagement with the

banks contacts in which conductors 808-810 associated with the line of substation A2 terminates.

The further operation at the end of the second digit depends upon whether the line is busy or idle. Assuming first that the line is busy, a ground potential is encountered on the test contact of conductor 808 by the test wiper of the connector and busy relay 829 is energized when the wipers come to rest, its circuit including contacts of the operated relay 830 and contacts of the non-operated relay 831. That being the case, relay 829 closes a locking circuit for itself at its inner upper armature when relay 830 falls back. With relay 829 thus locked operated, the rotary-magnet circuit is open so that further operations of the calling device at the operator's switchboard will not result in further movement of the connector. Upon the falling back of relay 830 a busy tone current from the busy tone lead is placed on the lower talking conductor, the upper talking conductor being grounded at this time at the upper contacts of relay 829 through the associated condenser and the upper contacts of relay 832. Upon hearing this busy tone, the calling operator knows that the called line is busy and is expected to withdraw her plug from the jack and allow the connection to release.

Assuming now that the line of substation A2 is idle when called, busy relay 830 is not operated when the wipers come into engagement with the bank contacts thereof, and, 100 when relay 830 falls back ground potential is applied to the test wiper at the upper armature of relay 830 from the inner upper armature of relay 827 through the inner upper armature of relay 829, lower winding of relay 831, and the upper armature of relay 830 to the test wiper. This application of ground potential results in the usual clearing of the called line, and in the operation of relay 831 to switch the connection through 110 to the called line.

The operator at the toll board now operates a ringing key of her cord circuit (or a special battery bridge key), whereupon relay 1005 responds and unbalances the circuit 115 over the toll trunk by opening the lower conductor thereof, whereupon differential relay 826, Fig. 8, responds and at its upper and lower armatures disconnects the line wipers from the repeating coil while at its inner 120 upper armature it closes a circuit through the middle upper armature, normal of relay 825 for the upper winding of the combined busy and ringing relay 830. Relay 830 responds and at its upper armature grounds the upper line wiper while at its middle 125 lower armature it places ringing current out on the lower line wiper so as to signal the subscriber at the called substation. The operator operates her ringing key in accord- 130

ance with her code assigned to the particular station on the called line, with the result that the called man's code is sent out.

Each time the operator restores her ringing key, relay 1005 falls back and balances the toll trunk whereupon relay 826 falls and opens the circuit of relay 830, which falls back and removes ringing current from the called line. It will be noted that a small condenser is connected between the upper right-hand repeating coil terminal of, Fig. 8, and the negative talking wiper and that another condenser is similarly connected between the lower left-hand repeating coil terminal and the positive wiper. These condensers are for the purpose of allowing just enough ringing current to pass back on the toll trunk so that the operator may hear the repeated ringing current in case she is energizing relay 1005 by an application of battery potential while her head set is connected up.

The toll connection is now completed to the line of substation A2 and the conversation may proceed as soon as the subscriber at the called substation responds.

When the connection is to be taken down, the operator at the toll board removes the plug from the jack J2, whereupon relays 1001 and 1002 fall back stopping the current flow over the toll trunk which results in a deenergization of relays 826 and 827, Fig. 8. The release magnet now energizes over the release signal conductor 201 through the off-normal contacts and-normally-closed contacts on relays 826 and 827, restoring the toll connector to its normal position whereupon the off-normal contacts open the circuit of the release magnet.

40 Handling an all trunks busy condition

It has been pointed out hereinbefore that there are more than ten local connectors and that two separate groups of line switches are provided, a master switch being assigned to each group of line switches. The connectors are divided into two groups, the first group being accessible to the first group of line switches, and the second group accessible to the second group of line switches. In Fig. 2, the terminals of the two groups are segregated, it being indicated whether the terminals are connector, master-switch, or line-switch terminals.

55 The way in which the operator is signalled when all trunks of a group become busy will not be explained. It will be noted, upon reference to Fig. 4, that the all-trunks-busy conductor 202 is normally grounded through the middle and upper ones of the three bottom test-jack springs and contacts of the switching through relay 436. Now, when the connector is in use, and relay 436 is operated, ground is removed at this point from the all trunks busy conductor, which conductor is

common to all the connectors of group #1. If an attendant or repair man desires to take the connector temporarily out of service while he makes minor repairs, he shifts the middle one of the lower three test jack contacts into engagement with the lower contact, extending a ground potential to the master switch test conductor 415 and removing ground at one point from the all-trunks-busy conductor.

Assuming now that ground potential is removed at all points from the all-trunks-busy conductor of connector group #1, conductor 202, Figs. 4 and 2, the normally energized relay 238 falls back. Upon so doing, relay 238 prepares at its inner lower armature a circuit through contacts of relay 239 for relay 240 over the ground-control conductor. The ground control conductor is maintained ungrounded by armature 350 of the cut-through relay 332 of the common sequence control equipment as long as a connection is being set up and until the common sequence control equipment clears out. When the equipment is cleared out, and ground is replaced on the ground control conductor, relay 240 operates through contacts of relays 238 and 239 and at its inner upper armature locks itself by means of its upper winding to contacts of relay 239. Upon operating, relay 240 closes a circuit from the now grounded control relay for relay 242. Relay 242 operates and opens the lower conductor of the operating trunks so that when relay 332 responds to the placing of battery on the common-locking-ground conductor at the lower contacts of relay 240, the current flow is momentarily unbalanced in the operating trunk, resulting in the operation of differential relay 333, Fig. 3, and in the operation of differential relay 115 Fig. 1. The operation of the differential ringing relay 333, Fig. 3 is merely incidental at this time and it does not cause any harm owing to the fact that the common sequence control equipment is not connected to any of the local connectors at this time.

In the operating center, relay 115 operates momentarily at the same time that relay 111 operates, and closes a circuit for relay 114, preventing an operation of relay 112, when relay 111 operates. Relay 114 operates and locks itself through the normally closed contacts of the release key at the special position, and at its upper armature it closes a circuit for the call lamp at the special position.

When relay 332 operates, it removes ground from the ground control conductor, whereupon slow-acting relay 242 falls back and again balances the operating trunk allowing relays 333 and 115 to reoperate.

Upon noting the lighted condition of the call-lamp associated with the operating trunk, the special position operator throws her answering key, extinguishing the call-lamp and

shifting the conductor formerly connected thereto to the winding of relay 113, operating relay 113 to connect her head set conductors to the talking conductors at its upper 5 and lower armatures. At its inner lower armature, relay 113 locks itself through contacts of the release key to the special position. At its inner upper armature, relay 113 disconnects the simplex leg of the operating 10 trunk from relay 111 and connects it to ground, deenergizing relay 111.

The operator now hears the busy tone placed on the upper talking conductor of the operating trunks by relay 238, Fig. 2, now deenergized, through contacts of relays 241 and 240. Upon hearing this busy tone, the operator 15 knows that all trunks in one of the groups are busy.

Upon receiving the information, the operator 20 restores her answering key and operates her release key momentarily. When the release key is operated, relays 113 and 114 are unlocked and fall back. As a further result of the operation of the release key, relay 104 25 is operated and locks itself to contacts of relay 103 as described hereinbefore. Relay 111 being deenergized and relay 104 being operated with relays 113 and 114 again deenergized, the circuits clear-out both in the operating 30 center and in the S. A. M. X. as hereinbefore described.

In the S. A. M. X., when line relay 334 falls back responsive to the clear-out operation in the operating center, it short circuits 35 release relay 335 in the usual manner and sends an impulse over the pulse conductor to the alarm and signal circuit of Fig. 2, operating relay 239 through contacts of relay 240. Relay 239, upon operating, locks itself to the 40 contacts of relay 238 at one of its upper armatures, and at its lower armature it opens the circuit of relay 240 which falls back leaving the alarm and signal relays in normal condition except that relay 238 is deenergized and 45 relay 239 is locked deenergized.

The operator having been informed of the busy condition of one of the groups in the S. A. M. X., the common equipment is now in readiness to handle further calls originating 50 in the group containing idle connectors.

The operator may now supervise the connectors in the S. A. M. X., or in case the condition manifests itself at a time when it is to be expected that all trunks are actually busy 55 she may forego this operation. At any rate, when a local trunk in the associated group again becomes idle, relay 238 falls back and unlocks relay 239 which renders the alarm and signal relays receptive again.

Handling an alarm call

In order to explain how an alarm call is handled, it will be assumed that one of the connectors becomes stuck or, for some other reason, fails to restore to normal position and 60

open the release magnet circuit when the release magnet circuit is closed. The various release magnets in the S. A. M. X. obtain their current through the release signal conductor of Fig. 2, which is connected to terminal 201 of connector group #1 and to terminals 209 of connector group #2. When relay 231 operates responsive to a regular release, the off-normal contacts open and relay 231 falls back so quickly that the slow-to-pull-up relay 233 does not have time to operate. However, when relay 231 remains operated for a substantial interval, relay 233 operates and closes a circuit through contacts of relay 239 for relay 241. Relay 241 operates and prepares to place a ringing tone on the negative trunk conductor at its upper armature; grounds the two chain-control conductors 205 and 214 which lead to the open-chain relays of the two master switches, respectively, so as to prevent further calls from coming in; and at its inner lower armature it prepares a circuit from the ground control conductor for relay 240.

From this point, the alarm call is handled 90 in the same way as an all-trunks-busy call previously described and the operator is informed of the alarm call by the ringing tone current instead of the busy tone. She accordingly makes a note of the condition.

Master switch alarm

In case the master switch operates in a normal manner and none of the relay contacts thereof remain closed for an undue length of time, ground potential is placed only momentarily on the alarm conductor 203 and relay 232 is operated only momentarily each time the master switch operates. In case the ground potential is maintained on conductor 203 from any one of the several sources in either of the master switches for a considerable length of time, relay 233 operates long enough to allow its vibrating contacts for an undue length of time to settle down sufficiently to operate the slow-to-pull-up relay 233 which brings in an alarm call in the same manner as described hereinbefore responsive to a release signal.

Line switch alarm

Upon referring to the line switch LS Fig. 1 it will be noted that the upper winding of the line relay is locked in series with the line-switch-alarm conductor common to all the line switches of both groups when the line relay operates and is transferred to the common locking conductor 208 when the line switch operates. Now, in case a line relay operates and line switch is defective so that it does not respond, the line relay circuit remains established through the line-switch-alarm conductor 206 for a substantial interval which results in the operation of relay 236, followed by the operation of slow-to-pull-up relay 235,

- only after the alarm ground has been restored on the alarm ground conductor by the common sequence control equipment. Shortly after relay 235 operates the slow-to-pull-up 5 relay 234 operates and locks itself to relay 236 and at its upper armature brings in the alarm in the manner hereinbefore described. The relays 234 and 235 are particularly slow to pull up so that they do not operate between 10 successive calls in case the preferential order of the chain arrangement is keeping a line switch from operating.

Supervising local connectors

- 15 It will now be assumed that the operator at the special position shown in part in Fig. 1 and in part in Fig. 10, having received an all-trunks-busy call from the S. A. M. X., wishes to ascertain whether all the local connectors 20 of one of the groups are actually in use or test busy due to an abnormal condition such as the failure to replace the receiver on the part of the calling subscriber. The operator at the special position is provided with cord circuits 25 similar to those used at the toll board and she has before her a multiple of the toll trunks.
- In order to supervise the local connectors, the operator at the special position of Fig. 10 inserts the plug of an idle cord circuit into the 30 jack of an idle toll trunk as indicated by the unlighted condition of the busy lamp, the toll trunk shown in the drawings for example, whereupon relays 1001 and 1002 operate in a manner hereinbefore described and prepare 35 the toll connector #1 Fig. 8 for operation by operating relays 826 and 827.

- In order to obtain access to the supervising switch which is connected to the "01" contacts of the toll connectors, the operator dial 40 the digits 0 and 1. When the digit 0 is dialled, the vertical magnet of the toll connector raises the wipers opposite the tenth level and the usual transfer of the impulsive circuit is made to the rotary magnet, and when the digit 45 1 is dialled the wipers are advanced one step into engagement with the "01" contacts. At this time the test wiper engages the "01" test contact which is not multiplied to the other toll connector banks as are the remaining 50 "01" contacts, whereupon the test wiper encounters a battery potential through relay 824, operating relay 824 in series with the lower winding of relay 831. Relay 831 operates in the same manner as in a regular call. 55 Relay 824 at its upper and lower armatures shunts the corresponding contacts of differential ringing relay 825; prepares to ground the release wiper under the control of relay 825 at its middle upper armature; and 60 at its inner upper armature it places ground on the junction of the right hand repeating coil windings through contacts of line relay 826, providing a circuit for operating the two windings of line relay 842 of the supervising 65 switch in parallel. Upon operating, relay

842 closes a circuit for release relay 841, preparing the supervising switch for operation.

In order to supervise the local connector #1, the operator at the special position dials the further digit 1, whereupon this digit is 70 repeated by line relay 826 in the circuit of the supervising-switch line relay 842. When relay 842 falls back it sends an impulse to the rotary magnet of the supervising switch, 75 advancing the wipers one step into engagement with the contacts in which the conductors 801-803 terminate.

With her listening key thrown, the operator 80 may listen in on the #1 local connector and ascertain whether it is in use or not. If the operator does not hear a conversation going on through the connector, she operates a key in her cord circuit to cause ringing current to be sent out over the toll trunk or, alternatively, she may operate a key to cause a difference of direct-current potential across the tip and ring conductors of the jack J1 to unbalance the trunk, by operating relay 1005 and operate the differential relay 825, Fig. 8. Upon operating, relay 825 grounds the release wiper through contacts of the operated relay 824, grounding the plus wiper of the supervising switch, which is now standing on conductor 803. When conductor 803 is grounded, relay 432 is shunted. If this relay 90 is operated due to a connection having been set up and the receiver left off, the relay falls back and releases the connection.

In order to supervise the next connector, 95 the operator dials an additional digit 1, whereupon the supervising switch is advanced an additional step, this being repeated until all the connectors have been supervised.

After supervising all the connectors and releasing those found operated, the operator 100 at the special position withdraws the plug from the jack, whereupon the associated relays fall back, and line relay 826 of the toll connector of Fig. 8 falls back and permits the connector to release, freeing the supervising switch with the result that the line and release relays thereof fall back and release the switch by energizing the release magnet through the associated off-normal contacts.

Key-ringing, ring-off release S. A. M. X. system

Referring now to the drawing assembly of Fig. 12 it will be explained how the key 115 ringing, ring-off release S. A. M. X., system operates to change to this layout, Fig. 8 is merely substituted for Fig. 5, it being assumed that the same line switch and master switch arrangement is used in connection 120 with Fig. 5 as is shown in Fig. 4. In the key-ringing, ring-off release system, the connector is seized responsive to the application of ringing current by the calling substation 125 in the manner hereinbefore described, and the 130

connecting relay 506 is operated over the hold conductor 414 responsive to the seizure of the connector in the manner hereinbefore described. Relay 504 is operated in multiple with relay 506 and it places a shunt around the ring-off relay 505.

The operator is signalled in the manner hereinbefore described, and when she responds and causes the sender to transmit the digits of the number, the vertical and rotary magnets operate in the manner pointed out hereinbefore, and the test of the line is made by the common sequence-control equipment as hereinbefore described.

When the ringing operation takes place, it is performed in the same manner as described before and when the clear-out time arrives, switching relay 503 is operated over the switch-through conductor 307, whereupon it connects the line wipers through and grounds the test wiper, at the same time locking itself to the holding conductor 414 and opening the circuit of the cut-through relay 506 and relay 504. Relay 506 falls back and disconnects the connector from the common equipment, but relay 504 remains operated for a short time so as to discharge the line before removing the shunt from around ring-down relay 505.

After the conversation has been completed, the calling subscriber "rings-off", whereupon relay 505, which is now connected across the incoming talking conductors 412 and 416 through contacts of relay 503 operates and closes a circuit through contacts of relay 503 for relay 501. Relay 501 operates and grounds release trunk conductor 413 at a new point at its upper armature, at the same time closing a circuit for release relay 502 at its lower armature. Relay 502 operates and removes the original ground from conductor 513 leaving this conductor grounded by the upper contacts of 501 as long as the ringing impulse endures.

When the impulse of ringing current is over, relay 505 falls back and permits relay 501 to fall back, whereupon conductor 413 is ungrounded and permits the line switch to release. When the line switch releases, conductor 514 is then grounded, whereupon relay 503 falls back and closes a circuit for the release magnet of the connector through contacts of relay 504 and the off-normal contacts associated with the release magnet. The battery for operating the release magnet is obtained through the release signal conductor 201 as indicated in the connector of Fig. 4.

It will be noted that there is a timing switch individual to the connector of Fig. 5. This timing switch is provided in order to release the connector at the end of an arbitrary period of five minutes, for example, so that in case the calling subscriber fails to "ring-off" the connection is released anyway in five minutes. The way in which this tim-

ing switch operates will now be explained.

With relay 503 operated after the connector has cut-through, the operating magnet of the timing switch is connected through contacts of the "0"-level springs to the combination 30-second impulse and tick-tone conductor with the result that an impulse is received by the operating magnet every thirty seconds. At the end of about four minutes, the left-hand wiper of the timing switch encounters a contact connected to the tick-tone conductor, whereupon a mild ticking tone is heard by both subscribers, warning them that the connection will be broken down in about another minute.

When the timing switch has reached its last step, the left-hand wiper thereof closes a circuit for relay 502, releasing the connector in the hereinbefore described manner. A branch circuit extends through the associated off-normal contacts to the release magnet of the timing switch, releasing the timing switch at the same time that the connector releases.

The release of the connector of Fig. 5 from the supervising switch of Fig. 8 when the operator is supervising the local connectors differs from the release described in connection in Fig. 4 in that the releasing impulse transmitted to the negative and release wipers of the supervising switch travels to the connector of G1. 5 over the release conductor 802, operating relay 501 to operate, which, in turn, operates relay 502 and release is jointly controlled by these relays in the same way as when a calling subscriber "rings-off".

When the connector is used in making a call over a toll trunk by way of the "0"-level of the contact bank, the "0"-level springs are operated, causing an operation of the "0"-level relay 338 over conductor 310, and at the same time opens a point in the circuit of the operating magnet of the timing switch so that the timing switch does not respond on a toll call.

In order to insure the prompt release of a toll connector on a toll call, whether the calling subscriber "rings-off" or not, the release conductor 806 in the trunk line leading to the toll connector #1 is provided and is connected with by the release wiper of the connector so that when the toll operator withdraws her plug after the connection has been set up and the conversation has been completed series 829 operates, when a momentary impulse is sent to the vertical magnet by the joint action of relays 827 and 828, and places ground momentarily on conductor 806 which extends through the release contact and the release wiper of the connector to relay 501 by way of contacts of the operated relay 503, causing the connector to release in the usual manner.

*Automatic-ringing, battery-holding
S. A. M. X. system*

The automatic-ringing, battery-holding layout is shown in Fig. 13 and involves Figs. 1-3, Fig. 6, and Figs. 9 and 10. When Fig. 1 is used, in the layout of Fig. 13 and in the layout of Fig. 14 it is necessary to remove the jumper 122, which ordinarily supplies ground potential to the armature of slow-acting relay 106, so as to avoid operating the counting relays 107 and 109. When these counting relays are not operated the impulse circuit first established for sending impulses over the operating trunk is not altered and all digits set up are transmitted to the S. A. M. X., the clearing-out being accomplished responsive to a closure of the switch-through contacts of the sender, which complete a circuit through contacts of the operated relay 1012 and contacts of the non-operated relay 1009 for relay 1004 so as to perform the clearing-out operation hereinbefore described.

Referring now to the connector shown in Fig. 6, it will be noted that this connector is the same as that shown in Fig. 4 except for the addition of the code selector shown to the right of the connector and in the addition of pick-up and stop relays 605 and 606. In the two connectors, the impedance 601 of Fig. 6 corresponds to the impedance 431 of Fig. 4, and the relays 432, 434 and 435 and 436 correspond to the relays 602, 604, and 607 respectively.

In order to explain the added portion of the connector shown in Fig. 6 it will be assumed that a call is being made through this connector and that the vertical and rotary impulses have been received by the vertical and rotary magnets, setting the wipers of the connector on the desired line. A busy test is made in the usual manner and the common sequence-control equipment transfers the operating circuit to the code-selector-operating conductor 312 with the result that the third digit, which is now received over the operating trunk instead of being absorbed in the operating center, as pointed out above, operates the code switch shown to the right is over the conductor 312 and through the right-hand contacts of connecting relay 621 by means of its rotary magnet. The wipers of the code selector come to rest on the bank contacts corresponding to the desired station of the called line.

When the relay 607 is operated over the switch-through conductor through the right-hand contacts of connecting relay 621, it locks itself to the hold conductor 414, at the same time opening the circuit of cut-through relay 621, disconnecting the connector from the common sequence-control-equipment. Relay 607 also prepares an energizing circuit for relay 605 over the pick-up conductor; prepares a locking circuit for the pick-up and stop relays 605 and 606; makes the usual

ground connection to test wiper at its middle upper armature; and at upper and lower armatures connects up the associated ring-back condensers so as to enable the operator and the calling subscriber to hear the ring-back tone when the ringing operation takes place.

When the pick-up conductor is grounded by the ringing machine, which may be the same as the code machine shown in Fig. 1, pick-up relay 605 operates and connects up the wipers of the code selector at its upper and lower armatures through resistances 608 and 609 to the negative and positive wipers of the connector. With the wipers thus connected up, the ringing operation takes place under the control of the ringing machine and in accordance with the code conductor selected. A return path to ground is provided at contacts of relay 605 over either wiper that happens to be standing on the return conductor while the other wiper is connected to a code conductor.

After the code has been transmitted, the stop conductor is grounded by the ringing machine in the usual manner, whereupon stop relay 606 is operated through contacts of cut-off relay 605 and closes a locking circuit for itself, opening its initial circuit at the same time, and also unlocking pick-up relay 605 and opening a point in the pick-up circuit. Stop relay 606 also closes the connection through from the calling line to the called line at its upper and lower armatures.

The conversation may now proceed in the usual manner and the connection is maintained operated by relay 603 under the control of line relay 602 until the calling subscriber replaces his receiver, whereupon the connector releases in the manner hereinbefore described. Relay 606 falls back when its locking circuit is opened by relay 607. The release magnet of the code selector operates from the connector in parallel with the release magnet of the connector and through its associated off-normal contacts. The release circuit of the connector includes normally closed contacts on switch-through relay 607 and on connecting relay 621.

The operation of this connector in being supervised and in calling to the toll operator over one of the toll trunks is the same as described in connection with Fig. 4.

Referring now to Fig. 9, the connector and supervising switch shown therein are very similar to the connector and supervising switch shown in Fig. 8, the difference lying in the provision of a code selector individual to the connector and the pick-up and stop relays 929 and 930 for controlling the application of ringing current. It will be noted that relays 921-923 corresponds respectively to relays 821-823; relays 824-828 correspond respectively to relays 924-928; and that relays 829, 830, and 831 correspond re-

spectively to relays 931, 932, and 933, relays 929 and 930 being added relays as above pointed out. Since the busy relay 931 does not have the added function of a ringing relay as does the relay 830, relay 931 has only one winding and does not have the ringing-current-repeating contacts.

In connection with the supervising switch, it is thought that the correspondence between these two switches is apparent upon a glance, as one is a copy of the other, relays 941 and 942 corresponding exactly to relays 841 and 842.

Assuming now that the toll connector at Fig. 9 is in use and that it has been set upon bank contacts of a called line, the next digit received is transmitted by line relay 926 through the lower armature of relay 927, operated, the associated normally open off-normal contacts, armature of relay 928, normal, inner lower contacts of busy relay 931, the inner lower armature, operated, of relay 933, and contacts of relay 924 to the rotary magnet of the code selector. The code selector advances its wipers onto a contact set corresponding to the desired station on the called line. Relay 932 is operated in parallel with the rotary magnet during the setting operation and when it falls back it completes a circuit at its lower contacts through the off-normal contacts of the code selector for reoperating busy relay 921 to connect up the ring back tone condensers through the upper and lower armatures of the operated switch through relay 933. The busy relay also connects the pick-up conductor through to the pick-up relay, by way of contacts of relay 933.

When the pick-up impulse is received, relay 930 operates and connects the wipers of the code selector to the corresponding wipers of the connector so as to permit the selected code to be sent out on the called line.

When the stop conductor is grounded at the end of the code period, the stop relay 929 is operated through contacts of the pick-up relay to close a locking circuit for itself and it completes the talking circuit and opens the ringing circuit at its upper and lower armatures.

When the operator withdraws her plug to release the toll connector, the locked up relays fall back and a circuit is closed for the release magnet of the connector through the associated off-normal contacts and through the contacts of relays 926 and 927 and a branch circuit extends through contacts of relay 931 for the release magnet of the code selector. Relay 931 remains operated and maintains this circuit closed until the off-normal contacts of the code selector open.

When the operator dials the digit combination 01 in order to obtain access to the supervising switch, the cut-through relay 933 operates in series with relay 924. Relay 924

prepares a circuit for grounding the release wiper and it opens the circuit of the rotary magnet of the code selector so as to prevent its operation at this time. At its inner lower armature, relay 924 closes a circuit for the lower winding of relay 929, operating this relay to close the connection through from the right-hand repeating coil winding to the wipers by way of contacts of the operated relay 924. The supervising switch is operated and any operated connectors may be released in the hereinbefore described manner.

*Automatic-ringing, ring-off release
S. A. M. X. system*

With reference to the layout of Fig. 14, the connector of Fig. 7 is similar to the connector of Fig. 5 except that it is provided with a code selector and the pick and stop relays 703 and 704. Relays 701 and 702 correspond to relays 501 and 502, and relays 705, 706, and 707 correspond respectively to relays 503, 504, and 505.

Assuming now that this connector is set on a called line and that the code selecting digit is received over conductor 312 from the common sequence-control equipment, the rotary magnet of the code selector operates and advances the wipers into engagement with the contact set corresponding to the desired station on the called line.

Now, when the switch-through impulse is received from the common sequence-control equipment over conductor 307 and through contacts of connecting relay 708, relay 705 operates and locks itself to the hold conductor 414, at the same time opening the circuit of relay 708 and of relay 706. Relay 708 falls back and disconnects the connector from the common sequence-control equipment and relay 706 falls back after an interval and removes shunt from around the ring-down relay 707. In addition to performing the usual cut-through function including the direct grounding of the test wiper and the connecting up of the release wiper, relay 705 connects up the ring-back condensers at its upper and lower armature so as to provide a path for ring-back tone, and it prepares a circuit for pick-up relay 703 from the pick-up conductor.

The pick-up and stop relays operate in the usual manner to control the application of ringing current and the stop relay completes the talking connection at the end of the ringing interval.

It will be noted that the timing device is started only after the stop relay operates, the circuit of the operating magnet thereof including "0"-level spring contacts, contacts of switch-through relay 705 and contacts of stop relay 704.

The timing device operates in the manner described in connection with Fig. 5.

When cut-through relay 705 operates when an outgoing toll call is being made, it closes a

circuit from the grounded "0" level conductor through its inner upper contacts for stop relay 704 to complete the cut-through operation without waiting for ringing current to be applied from the connector.

Handling reverting calls

The method of handling reverting calls in the four-layouts of Figs. 11-14 will now be explained. Referring now particularly to Fig. 4, it will be noted that the line winding of the line relay 404 of the line switch is connected by means of the jumper 417 directly across the conductors 401 and 403 of the line 15 of substation A1. This is the arrangement used when the subscribers' stations are not provided with grounding push-buttons, and its use is usually confined to the battery-holding lines whereon no party-to-party calls 20 on the same line are to be made. In case party-to-party calls on the same line are to be made in either of the battery holding layouts, Figs. 11 and 13, it is considered necessary to disconnect the jumper 417 from the 25 upper line conductor 401 and connect it to ground and to provide the magneto substations from push-buttons so that a subscriber can ring in the usual way and signal another party on the same line without operating the line relay 404, and can push the button and provide the generator with a ground return so as to operate relay 404 when he desires to 30 signal the operator. It may be pointed out that, when desired, this same arrangement 35 may be employed in connection with the ring-off release layouts of Figs. 12 and 14. This however, is not required in the ring-off release layout using the connectors of Figs. 5 and 7, owing to the fact that a very simple reverting call arrangement can be employed as the calling subscriber's in the ring-off release 40 system can replace their receivers and wait for a reverting ring without releasing the connection.

Referring now particularly to Figs. 3 and 5, it will be assumed that a subscriber has obtained connection with the connector of Fig. 5 and has been connected with the operator in the usual manner through the operating trunk and that he informs the operator that he desires to converse with another subscriber on the same line.

Upon receiving this request, the operator sets up on the key set the digit combination 55 90 followed by the digit assigned to the particular party desired on the called line. As a result, the vertical and rotary magnets of the connector of Fig. 5 are operated to bring the wipers into engagement with the "90" set of 60 bank contacts. When this occurs, the reverting-call relay 347, Fig. 3, is operated over the "90" test contact and conductor 313 in the same way that the cut-off relay of a called line is operated, and it locks itself through 65 its upper winding and through contacts of

the operated relay 344, opening the circuit of relay 346 so as to prevent this line from operating responsive to the usual operation of switching relay 341.

In the connector of Fig. 5, the "90" springs 70 of the connector are shifted when the connector is set in "90" position, disconnecting the incoming trunk conductors 412 and 416 from corresponding conductors 302 and 301 of the common equipment and connecting them instead to the negative and positive wipers so that the ringing current received from the common sequence control equipment under the control of differential relay 333, which is in turn controlled in the usual manner is sent back to the calling line, the calling subscriber having been requested to replace his receiver during the ringing operation.

When the common sequence control equipment clears out at this time, relay 347 is 85 operated and has prepared a release circuit by preventing the operation of relay 346 so that when relay 345 is momentarily operated a release circuit is closed over release conductor 306 to release the connector so as to prevent tying up the central office equipment 90 while parties are conversing on the same line.

Referring now to Fig. 7 in connection with Fig. 3, in this case when a reverting call is 95 asked for, the digits 9 and 0 are sent over the operating trunk from the operating center followed by the digit indicating the desired station on the called line, which latter digit 100 operates the code selector associated with the connector in Fig. 7. The operation of the code selector is followed by the hereinbefore-described operation of the pick-up and stop relays with transmission of ringing current intervening between. In this case, the reverting-call relay 347 in the common sequence control equipment is not operated with the result that when the switch-through impulse comes just after the code selector is positioned 105 the switch through relay 705 is operated and connector is not released at this time as in the case of Fig. 5. When the "90" springs 110 operated, the ringing current supplied to the wipers of the connector from the code selector is transmitted back to the calling line. It is not necessary to arrange the "90" 115 springs in this case to disconnect the plus trunk and minus trunk conductors of the common sequence control equipment owing to the fact that connecting relay 708 falls back before the ringing current is applied. When the stop relay is operated, relay 702 is 120 operated in parallel therewith through "90" springs, releasing the connector.

Emergency operating set

Wherein, during an emergency, the operating trunk is out of order, an operator is sent to the S. A. M. X. to set up the connections through the emergency set of Fig. 2. The 125 130

operator throws the transfer key opening the regular operating trunk, and connecting up the emergency set. Now when a call comes in the call lamp lights over the call lamp conductors, whereupon she throws her answering key and handles the connection, setting the switching apparatus by means of the calling device CD and controlling ringing by unbalancing the circuit by means of the ringing key.

10 The operator restores the answering key to clear out the equipment.

What is claimed is:

1. In a telephone system wherein an automatic exchange is arranged to be controlled from a remote point over an operating trunk, ringing current repeating apparatus in said exchange arranged to be controlled over said trunk, and means for setting the automatic

20 switching apparatus in the semi-automatic exchange to complete a connection and for controlling the ringing-current repeating apparatus over the operating trunk to signal the desired station on a called party line.

25 2. As an article of manufacture, a common sequence-control equipment arranged to be used on the semi-automatic magneto-exchange end of an operating trunk connecting the semi-automatic magneto exchange with

30 an operating center, and means in said common sequence control equipment enabling it to cooperate with a plurality of different types of switching apparatus.

35 3. In a telephone system, a plurality of lines entering an automatic exchange, a group of automatic switches common to said lines, non-numerical switching apparatus arranged to connect any calling line with an idle one of said automatic switches, a control unit common to all said automatic switches, means responsive to a calling line being connected with an idle one of said automatic switches for effecting a connection between such automatic switch and said common control unit,

40 45 means for severing the connection between the automatic switch and the common control units after the automatic switch has been positioned in accordance with the destination of the call, and means for preventing operation of said non-numerical switching apparatus while the common control unit is connected to an automatic switch.

50 55 60 65 4. In a telephone system wherein subscribers' lines entering an exchange terminate in line switches having access to automatic switches, a control unit common to said automatic switches, means responsive to a seizure of any one of said automatic switches by a line switch for connecting the control unit to said automatic switch so as to enable the automatic switch to be operated and for disconnecting the automatic switch from the control unit after the automatic switch has been operated, and means for preventing the operation of any further line switches during

the time that the automatic switch seized by the first operated line switch is connected to said common control unit.

5. In a telephone system wherein automatic connector switches have access to subscribers' lines, a control unit common to said connector switches, means for taking any one of said connector switches for use and for connecting it with said control unit, means for operating the connector switch taken for use into association with a called line, and circuit arrangements including a testing relay in said common control unit controlled through said connector switch from the test conductor of the called line for determining the busy or idle condition of the called line and for enabling the connector to make or deny the connection.

6. In a telephone system wherein automatic connector switches have access to subscribers' lines, a control unit common to said connector switches, means for taking any one of said connector switches for use and for connecting it with said control unit, means for operating the connector switch taken for use into association with a called line, and means including a ringing relay in said common unit for applying ringing current to a called line through the operated connector.

7. In a telephone system wherein connections from subscribers' lines are extended through automatic switching mechanism to automatic switches and wherein the automatic switches are operated from an operator's switchboard over a circuit path excluding connections set up from the subscribers' lines to the automatic switches, means associated with the automatic switches and controlled from the operator's switchboard after the connection has been set up to a line for initiating and terminating an application of ringing current to a called line, the length of such application being controlled from the operator's switchboard.

8. In a telephone system, an operating trunk extending from a manual switchboard to an automatic switchboard, automatic switch at said automatic switchboard, means for setting up a connection from a calling line to one of said automatic switches and for setting up an independent connection from said manual switchboard over said operating trunk to the same automatic switch, means controlled from said manual switchboard for operating said automatic switch to set up a connection to a called line, means at the manual switchboard for transmitting over said operating trunk an additional impulse to the automatic switchboard after the connection is set up, and means at the automatic switchboard responsive to such impulse for making an application of ringing current to the called line of a duration corresponding to the duration of said impulse.

9. In a telephone system, an operating

trunk extending from a manual switchboard to an automatic switchboard, automatic switches at said automatic switchboard, means for setting up a connection from a calling line to one of said automatic switches 5 and for setting up an independent connection from said manual switchboard over said operated trunk to the same automatic switch, means controlled from said manual switchboard for operating said automatic switch to set up a connection to a called line, means for transmitting a code of impulses over said operating trunk from the manual switchboard to the automatic switchboard after the connection is set up, and repeating means at 10 the automatic switchboard responsive to each impulse of the code to transmit an impulse of ringing current to the called line of a duration depending upon the corresponding impulse 15 received over the operating trunk from the manual switchboard.

10. In a telephone system wherein an automatic switch is operated over a trunk line outgoing from a manual switchboard to an automatic switchboard to set up a connection to a called party line, there being a distinctive code assigned to the respective stations on said line, keys at said switchboard corresponding to said codes, respectively, and 25 means for transmitting over said trunk line impulses corresponding to the code to which any operated key corresponds.

11. In a telephone system wherein an automatic switch is operated over a trunk line outgoing from a manual switchboard to an automatic switchboard to set up a connection to a called party line, there being a distinctive code assigned to the respective stations on said line, keys at said switchboard corresponding to said codes, respectively, 30 means for transmitting over said trunk line impulses corresponding to the code to which any depressed key corresponds, and means responsive to the impulses transmitted over said trunk line for repeating corresponding impulses of ringing current to the called party line to signal the desired station thereon.

12. In a telephone system wherein an automatic switch is operated over a trunk line outgoing from a manual switchboard to the said switch to set up the connection to a party line, a plurality of keys at said manual switchboard corresponding respectively to 55 the stations on said party line and arranged so that any one of them may be depressed by the operator, the one depressed depending upon the particular station desired, means at the manual switchboard for transmitting over said trunk line a combination of impulses depending upon the key depressed whereby the called station on the party line is signalled.

13. In a telephone system wherein an automatic switch is operated over a trunk line

outgoing from a manual switchboard to the said switch to set up the connection to a party line, a plurality of keys at said manual switchboard corresponding respectively to the stations on said party line and arranged 70 so that any one of them may be depressed by the operator, the one depressed depending upon the particular station desired, means at the manual switchboard for transmitting over said trunk line a combination of impulses depending upon the key depressed, and repeating means associated with the automatic switch and responsive to each of the said impulses of the transmitted code to transmit a corresponding impulse of ringing 75 current to the called line.

14. In a telephone system wherein a connection set up from a manual switchboard through an automatic switch to a called line includes a trunk line over which the connection is held up by current flow over the two sides of the line in parallel and through a separate return, means controlled from the manual switchboard for unbalancing the current flow in the two conductors of said line in accordance with a code assigned to the called station on the party line, and a repeating device on the distant end of said trunk line responsive each time the trunk line is unbalanced to repeat an impulse of ringing current 80 to the called line.

15. The method of setting up telephone connections through automatic switching apparatus to party lines having a plurality of stations thereon which consists in storing the 85 number assigned to a desired party line and in storing the designation of the desired station on the called line, in operating the automatic switching apparatus in accordance with the stored number by transmitting 90 series of impulses of one kind to the automatic switching apparatus, and in signalling the desired station on the called line by transmitting impulses of a different kind in accordance with the stored stations designation. 95

16. In a telephone system wherein automatic switching apparatus in a semi-automatic exchange is operated over an operating trunk from an operating exchange to set up 100 connections in said semi-automatic exchange, means responsive to a call in the semi-automatic exchange for extending a connection from the calling line over the operating trunk to the operating exchange and for signalling the regular operator 105 thereat by imposing a given condition on said operating trunk, and means responsive to an abnormal condition within the semi-automatic exchange for extending a connection over the operating trunk to the operating 110 exchange and for signalling the special operator thereat by imposing a specifically different condition on said operating trunk.

17. A telephone system as claimed in claim 115 16 in which the first mentioned condition 120

- placed on the operating trunk consists in setting up a current flow of substantially equal strength over the two sides of the operating trunk and in which the second condition is 5 a current flow of unequal strength in the two sides of the operating trunk.
18. In a telephone system, a first exchange, a second exchange, two switchboards at the second exchange, a differential relay in the 10 second exchange, means for seizing said trunk line in the first exchange under one condition and for setting up a current flow over the two sides thereof of substantially equal value, means in the second exchange responsive thereto for signalling the operator at one switchboard, means for seizing said operating trunk under another condition and for setting up a current flow in one conductor which exceeds the current flow in the other conductor 15 of the trunk line, and means including said differential relay in the second exchange responsive to the unbalanced current flow for signalling the operator at the other switchboard instead of the operator at the first 20 switchboard.
19. In a semi-automatic telephone system wherein a semi-automatic exchange is remotely controlled over an operating trunk from a manual exchange, a regular position 25 in said manual exchange equipped for handling regular connections in the semi-automatic exchange, a special position in the manual exchange, means for seizing the operating trunk in the semi-automatic exchange responsive to a regular call, means in the manual exchange responsive thereto for signalling the operator at the regular position, means for seizing said operating trunk in the semi-automatic exchange responsive to an abnormal 30 condition therein, and means in the manual exchange responsive to the last named seizure for automatically signalling the operator at the special position instead of the operator at the regular position.
- 40 20. In a semi-automatic telephone system, two groups of automatic switches accessible, respectively, to two groups of subscribers' lines through line switches, there being a line switch individual to each of said subscriber's lines, each group of line switches being under 45 control of a separate master switch, means responsive to a call on any line for operating the line switch individual thereto to seize an idle switch in the corresponding group, means for signalling the semi-automatic operator when such connection is made and for preventing the operation of any other line switch in either group, and means responsive to the completion of the control of said automatic switch by the operator for enabling the line switches to become operated.
- 50 21. In a telephone system, two master switches, two groups of line switches controlled respectively, by said master switches, a chain circuit so arranged that any line 55

switch upon operating momentarily prevents the operation of all succeeding line switches in the chain circuit from operating, said chain circuit being provided in duplicate, one chain circuit for each group of line switches, circuit connections for connecting the two chains in series when there are trunk lines available to both line switches, and means effective when all trunks become busy to one group of line switches for opening the chain to such group and for completing the chain to the second group over an independent path. 70

22. In a telephone system wherein automatic switches are operated over an operating trunk, said switches being divided into two groups and being accessible respectively to two groups of non-numerical switches, means responsive to the seizure of a switch in either group by one of said non-numerical switches for rendering the remaining non-numerical switches of both groups inoperative to seize further ones of said automatic switches, and means responsive to the seized automatic switch being operated over said operating trunk for again rendering the non-numerical switches operative. 80

23. In a telephone system wherein a connection set up from a manual switchboard through an automatic switch to a called line includes a trunk line over which the connection is held up by current flow over the two sides of the line in parallel and through a separate return, means controlled from the manual switchboard for unbalancing the current flow in the two conductors of said line in accordance with a code assigned to the called station on the party line, and means including a differential relay having two windings connected in the two sides of the line, respectively, and responsive to each unbalancing of the line to repeat a corresponding impulse of ringing current to the called line. 95

24. In combination, a plunger line switch having a line relay and a plunger-operating magnet, means including contacts on the line relay effective when the line relay is operated to close a circuit for said magnet and for closing an alarm circuit, and contacts on said magnet for opening the alarm circuit when the magnet operates. 100

25. In combination, a plunger line switch having a line relay and a plunger-operating magnet, an alarm device, and means including contacts on said line relay effective when the line relay is operated to close a locking circuit for said line relay in series with said alarm device and to close an operating circuit for said magnet. 115

26. In combination, a plunger lineswitch having a line relay and a plunger-operating magnet, an alarm device, means including contacts on said line relay effective when the line relay is operated to close a locking circuit 120

for said line relay in series with said alarm device and to close an operating circuit for said magnet, and contacts on said magnet for excluding said alarm device from said locking circuit.

27. In combination, a plurality of line-switches each having a line relay, switching devices accessible to said line switches, contacts on any line relay effective when the line relay is operated to close a locking circuit for the line relay and to operate the lineswitch to seize one of said devices, operating means common to said devices, means responsive to a seizure of any device for associating the common operating means therewith, and means controlled over said locking circuit for preparing the said common means for operation.

28. In a semi-automatic telephone system, automatic switching devices arranged to be directly operated to set up connections between subscribers' lines, a trunk line over which the directive operation of any device is controlled, non-numerical switching apparatus operable over any calling line to effect a connection between such line and one of said devices, means responsive to the said operation of the non-numerical apparatus for connecting said trunk line and the switching device taken for use, a separate connection between the calling line and the trunk line and independent of the switching device taken for use, and means in the trunk line controlled over said separate connection for placing the trunk line in condition for the said control to be exercised thereover.

29. In a semi-automatic magneto telephone system wherein automatic switches are controlled from an operator's switchboard to set up connections from subscribers' lines, hand generators on said lines, non-numerical switching apparatus responsive to current from the generator on a line to effect a connection from such line to one of the automatic switches, and means also responsive to said current for signalling the operator at said switchboard by means of a circuit from said line excluding the first-named connection.

30. In a semi-automatic telephone system, automatic switching devices each having an operating magnet, a trunk line extending from said devices to an operator's switchboard, means for connecting a calling subscriber's line with one of said switching devices and for connecting the switching device with said trunk line, and means in said trunk line controlled from said switchboard for sending impulses directly to the operating magnet of the connected switch.

31. In a semi-automatic telephone system, automatic switching devices each having two operating magnets, a trunk line extending from said devices to an operator's switchboard, means for connecting a calling sub-

scriber's line with one of said switching devices and for connecting the switching device with said trunk line, and means in said trunk line controlled from said switchboard for sending impulses constituting a digit of a desired number directly to one operating magnet of the connected switch and for subsequently sending impulses comprising a further digit in the same number directly to the other operating magnet of the connected switch.

32. In a semi-automatic telephone system, automatic switching devices having access to subscriber lines, each of said switching devices having an operating magnet, a trunk line extending from said devices to an operator's switchboard, means for connecting a calling subscriber's line with one of said switching devices and for connecting the switching device with said trunk line, means in said trunk line controlled from said switchboard for sending impulses directly to the operating magnet of the connected switch, to set the connected switch on the line of a called subscriber, and means in said trunk line and controlled through the connected switch for testing the called line to ascertain its busy or idle condition.

33. In a semi-automatic telephone system, automatic switching devices having access to subscriber lines, each of said switching devices having an operating magnet, a trunk line extending from said devices to an operator's switchboard, means for connecting a calling subscriber's line with one of said switching devices and for connecting the switching device with said trunk line, means in said trunk line controlled from said switchboard for sending impulses directly to the operating magnet of the connected switch, to set the connected switch on the line of a called subscriber, and means in said switch and controlled from said trunk line in accordance with the busy or idle condition of the called line to effect or deny connection to the called line depending upon its condition.

34. In a telephone system, connector switches, a toll line accessible by way of said connector switches and terminating in a toll switch, and a connector-supervising switch accessible to said toll switch and having access to said connector switches.

35. In a telephone system, a toll line terminating in a toll switch having access to subscribers' lines, local switches having access to said subscribers' lines and to said toll line, and a supervisory switch accessible to said toll switch and having access to said local switches.

36. In a telephone exchange system, trunk lines specific to an exchange, means including automatic switching apparatus in said exchange for setting up telephone connections through said trunk lines, a toll line

- entering said exchange, a supervising switch, automatic switching apparatus controllable over said toll line to extend the toll line to a subscriber's line or to said supervising switch, and means effective when the connection is extended to the supervising switch for operating such switch over the toll line to make a supervising connection with any one of said trunk lines.
37. In a telephone system, a telephone exchange, automatic switches in said exchange common to the subscribers' lines thereof and arranged to set up telephone connections involving said subscribers' lines, other automatic switches in said exchange, and means for setting up a supervising connection through two of said other automatic switches in serial relationship to any one of the first-named automatic switches.
38. In a telephone system, a telephone exchange, automatic switches in said exchange common to the subscribers' lines thereof and arranged to set up telephone connections involving said subscribers' lines, other automatic switches in said exchange, means for setting up a supervising connection through two of said other automatic switches in serial relationship to any one of the first-named automatic switches, and means controlled over the supervising connection for releasing any one of the first-named switches that happens to be operated when the supervising connection is extended thereto.
39. In a telephone system automatic switches arranged to be operated to set up telephone connections, a line relay in each switch arranged to be held up over a connected line to maintain an established connection, means for setting up a supervising connection to any one of said switches whether it is operated or not, and means controlled over the supervisory connection for restoring the line relay of the connected automatic switch to release the telephone connection set up therethrough.
40. In a telephone system, a trunk line, automatic switches each having an operating magnet, means for extending a connection from a calling line to one of said switches and for connecting such switch to said trunk line, and means controlled over said trunk line and common to all said switches for sending operating impulses directly to the operating magnet of the connected switch.
41. In a telephone system, a trunk line, automatic switches each having two operating magnets, means for extending a connection from a calling line to any one of said switches and for connecting such switch to said trunk line, and means controlled over the trunk line and common to all of said switches for sending a series of operating impulses directly to the first of the operating magnets of the connected switch and for then sending a series of impulses directly to the second operating magnet of the connected switch.
42. In a telephone system, a trunk line, automatic switches having access to lines, means for extending a connection from a calling line to any one of said switches and for connecting such switch with said trunk line, means controlled over said trunk line for operating the connected switch into association with one of the lines accessible thereto, and means in said trunk line and common to all said automatic switches for testing the line with which association has been made.
43. In a telephone system, a plurality of automatic trunk-hunting switches, trunk lines accessible thereto, a control trunk line, means for extending a connection from a calling line to any one of said automatic switches and for connecting said control trunk line thereto, means responsive to control exercised over said control trunk line for bringing the connected automatic switch into association with a group of trunk lines, and means in said control trunk line and common to all said switches for operating the connected switch step-by-step over the trunk lines in the selected group and for stopping the switch on an idle one, said means in the control trunk line including means for testing the selected trunk lines one at a time as they are connected with by the connected hunting switch.
44. In combination, two master switches, two groups of lineswitches controlled by said two master switches, respectively, trunk lines accessible to said line switches, said master switches being operable to select idle trunk lines, and circuit arrangements for rendering all the lineswitches operative dependent upon the selection of a trunk line by one of the master switches.
45. In a telephone system employing automatic switches, two trunk selecting master switches two groups of line switches controlled by said master switches, respectively, and means for preventing operation of any of said lineswitches if one of said master switches has not selected a trunk.
46. In a telephone system employing automatic switches, a group of lineswitches, two master switches, an operating circuit for all of the lineswitches controlled by one of said master switches, and means for shifting the operating circuits for a part of the lineswitches under control of the other master switch.
47. In a telephone system, a plurality of combination and non-hunting connectors, control equipment common to all said connectors, means for associating the common equipment with any connector, and means in the common equipment for causing an associated connector to function either as a hunting connector or as a non-hunting connector.
48. In a telephone system, a plurality of

combination hunting and non-hunting connectors, and means common to all of said connectors and controlled from any one of them for converting any one of them from a
5 non-hunting connector to a hunting connector.

In witness whereof, I hereunto subscribe my name this 4th day of August, A. D. 1928.

EDWARD S. PETERSON.

10 In witness whereof, I hereunto subscribe my name this 4th day of August, A. D. 1928.

LEONARD L. RUGGLES.
